UNITED STATES PATENT OFFICE.

WILLIAM J. KENNEY, OF CHICAGO, ILLINOIS, ASSIGNOR TO THE UNDERFEED STOKER COMPANY OF AMERICA, OF CHICAGO, ILLINOIS, A CORPORATION OF NEW JERSEY.

AUTOMATIC STOKER.

1,035,359.

Specification of Letters Patent. Patented Aug. 13, 1912.

Application filed December 30, 1907. Serial No. 408,572.

To all whom it may concern:

Be it known that I, WILLIAM J. KENNEY, a citizen of the United States, residing at Chicago, in the county of Cook and State 5 of Illinois, have invented a certain new and useful Improvement in Automatic Stokers, (Case 2,) of which the following is a full, clear, concise, and exact description, reference being had to the accompanying drawings, forming a part of this specification.

My invention relates to improvements in automatic stokers, and particularly to that class known as underfeed stokers.

15 It is an object of my invention to construct a retort for a stoker of the class indicated in such a manner that it may be free from the usual tendency to crack, due to the excessive expansion and contraction 20 strains occasioned by the combustion of the fuel delivered to the fire by the retort. This I accomplish by constructing the portion of the retort that is most subjected to such strains in a plurality of sections, and securing 25 these sections together by means of bolts.

It is a further object of my invention to construct twyer blocks of greater efficiency 30 and less weight than heretofore in use, a result of such construction being that the air is used more effectively, that there is a greater air opening per twyer block, and that the air is uniformly distributed 35 through a plurality of openings in such block. In my improved construction, the twyer blocks are made comparatively narrow, as a result of which their life is increased as they are protected from ashes accumulating upon them and burning them 40 out.

It is a further object of my invention to improve the construction of the deflector plate over the front end of the retort in such a manner that this deflector plate may 45 be independent of the means used to support the brickwork of the boiler over the front end of the retort, and to this end I employ separate means for supporting this brickwork, or front pier of the boiler and 50 proportion the retort and front twyer blocks in such a manner that by removing the front twyer block on each side of the retort, the deflector plate may be either inserted or removed from the rear of the 55 front pier, and when in place requires no

additional holding means, from which it will be seen that my improved deflector plate may be readily replaced without disturbing the boiler setting in the least.

The several drawings illustrating my invention are as follows:

Figure 1 is a view partially in vertical section of my improved retort, twyer blocks and deflecting plate associated with a boiler and underfeed stoker mechanism; Fig. 2 is 60 a vertical sectional view taken along line 2-2 in Fig. 1; Fig. 3 is a similar vertical sectional view taken along the line 3-3 in Fig. 1; Fig. 4 is a similar sectional view taken along the line 4-4 in Fig. 1; Fig. 5 65 is a perspective view of the supporting plate or beam used to support the front pier of the boiler; Fig. 6 is a perspective view of my improved deflector plate; Fig. 7 is a perspective view of a blank twyer block 70 constructed to correspond with my improved design; Fig. 8 is a detailed face view of one form of my improved twyer block, while Fig. 9 is a sectional view of this block taken along the line 9-9 in Fig. 8; 80 Figs. 10 and 11 are views similar to Figs. 8 and 9 of a modified form of my improved twyer block.

Similar numerals refer to similar parts 85 throughout the several views.

Referring to the drawings, 17 represents a boiler supported in part by the pier 16 having a usual front plate 18, in the lower part of which an opening is formed to receive the front end of the retort 8 to which the stoking mechanism is secured in front of the boiler. This mechanism consists of a ram 6, adapted to be reciprocated by suitable means as a steam cylinder 7 below the lower end of the hopper 5, as a result of which fuel deposited in the hopper 5 is fed into the compartment 25 in front of the ram 6, and by the reciprocation of this ram is fed into the front end of the retort 8, and as successive charges of fuel are forced into the retort 8, the fuel is fed backward and upward to a position to be consumed under the boiler 17. A push bar 12 is rigidly attached to the ram 6, as indicated, and has secured thereto the tapered blocks 13, 13, which serve to agitate the fuel and direct it upwardly. The retort 8, as indicated, is split along a line parallel with the upper surface thereof and at such a distance below that the parts of the retort above this dividing line 100 105 110

will receive practically all of the excessive heating due to the combustion of the fuel, while the portion below this dividing line will not be unduly heated. It is noticed that the portion of the retort above this dividing line is divided into a plurality of sections 10, 10, all of which are bolted together and to the main section of the retort 8, as indicated, by which any one of the upper sections may be readily replaced when necessary. The upper faces of the sections 10, 10 are conformed to receive the twyer blocks 19 and 20, through the lugs of which bolts 21 are adapted to pass to secure such twyer blocks in position. The front pier 16 of the boiler is supported by means of a plate or beam 15, preferably of cast iron, which in turn is supported from the front end of the retort and is so conformed that the deflector plate 14 may be inserted beneath the front pier 16 and the beam 15 and be securely held in such position by inserting the blank twyer blocks 19. When in such position as will be seen by referring to Fig. 2, the deflector plate is in such a position that openings 14^b, 14^b in such deflector plate register with corresponding openings in the upper flanges of the sections 10, 10, while the tapered portions 14^c, 14^c serve to hold the deflector plate 14 securely in position. This deflector plate is hollow, as indicated, and the openings 14^b, 14^b communicate with the holes 14^a for the purpose of directing air into the fuel to properly aid in the combustion of the same and also to prevent gases of combustion from passing out through the chamber 25 into the hopper 5. The top flanges of the retort are adapted to support plates 24, 24, the outer edges of which are supported from the walls 23, 23 of the boiler setting, and these plates and walls together form an air compartment under and around the retort, into which air is fed by any suitable means not shown, and as a result is supplied to the deflector plate 14 through the openings already indicated.

The twyer blocks 20 shown in Figs. 8 and 9 in detail, are practically twice as long as twyer blocks heretofore used in connection with devices of this sort, as a result of which the air openings 20^a in one of such blocks are longer than it has been possible heretofore to make these openings since a single thickness of reinforcing web 20^c is required at the middle of each block instead of a double wall of material, as would be required if there were a joint between blocks at this point. It will be noticed that the ribs 20^e form supply passages between their rear edges and the back wall of the twyer block smaller than the air-supply passages formed in the bases of the twyer blocks below the lower opening 20^a, as a result of which such ribs serve to distribute the air uniformly to the outlet openings, as well as

to engage and direct the air to the openings below them. Lugs 20^a, 20^a are provided and have formed therein holes 20^b, 20^b to be engaged by a suitable bolt, as 21, to hold these twyer blocks in position upon the top flange of the retort

The twyer block 26 shown in Figs. 10 and 11 is similar to the twyer block 20 shown in Figs 8 and 9, with the exception that there are four parallel openings 26^a in each section of this block 26, and that these openings are separated by the ribs 26^e. The ribs 26^e thus formed, besides serving to bound the outlet openings, also form supply passages between their rear edges and the back wall of the twyer block, which supply passages are roughly proportioned to the combined area of the outlet openings that must be supplied by them. Thus the air supplied to each block is directed into the several openings, and the air supplied to the several openings is uniformly distributed by means of these ribs 26^e.

From the construction of the twyer blocks 20, 20 above described, it will be seen that the dead plates 24, 24 can be made comparatively wider than in previous constructions, in which the twyer blocks were proportioned to be practically the height indicated in this application, and about twice as wide. The advantage of the present construction in this respect is that the cinders and ashes formed by the combustion of the fuel have a greater area to collect on, and there is a greatly diminished tendency of the ashes and cinders to collect on and about the twyer blocks 20, and thus overheat and burn them.

While I have shown my invention in the embodiment above described, I do not, however, limit myself to this particular construction, but desire to secure by Letters Patent any equivalent modifications that may suggest themselves to those skilled in the art.

What I claim is:

1. In combination in a furnace, a retort for receiving fuel to be consumed, a beam supported by the front end of such retort and adapted to carry the weight of the front wall of the furnace, removable twyer blocks supported by such retort, and a deflecting plate adapted to be supported by such retort over the entering fuel and under such beam, such deflecting plate adapted to direct the fuel upward in the retort and so conformed as to be insertable and removable from the rear of the front wall by removing the twyer blocks adjacent to such front wall.

2. In combination, a furnace, a retort disposed in the furnace, a beam supported by the front end of such retort and adapted to carry the weight of the front wall of the furnace, removable twyer blocks supported by the retort, and a hollow deflecting plate

adapted to be supported by such retort over the entering fuel and under such beam, such deflecting plate adapted to direct the fuel upward in the retort and so formed as to be 5 insertible and removable from the rear of the front wall through the space normally occupied by the adjacent twyer blocks by first removing such twyer blocks, the retort and deflector plate adapted by their coöperation to direct air under pressure from beneath and around the retort through the deflector plate into the fuel.

3. A twyer block for use in an underfeed stoker consisting of an elongated narrow hollow member open along one side and closed on the remaining sides, said member having outlet openings in a side adjacent to the aforesaid open side, and a partition wall arranged within said member in a plane 15 transverse to the open side thereof.

4. A twyer block for use in an underfeed stoker consisting of an elongated hollow member open on one of its long sides and closed on the remaining sides, there being 25 elongated slots in one of the long sides adjacent to the aforesaid open side, and a dividing wall extending across the interior of said member in a plane transverse to the said walls.

30 5. A twyer block for use in an underfeed stoker consisting of an elongated hollow member open on one of its long sides and closed on the remaining sides, there being two series of elongated openings extending 35 lengthwise in a second long side of said member adjacent to the aforesaid side, and a dividing wall extending across the interior of said member between said series of open-

ings and in a plane transverse to the wall containing said openings.

40 6. A twyer block for use in an underfeed stoker comprising an elongated hollow member open on one of its long sides and closed on the remaining sides, the width of the open side being less than the depth of said member measured at right angles to that side, the parts being so proportioned that the chamber within said member narrows in the transverse direction from said open side toward the side opposite thereto, and one of the sides adjacent to said open side being 45 provided with a series of openings distributed transversely of the same.

7. In combination, an open-topped retort having laterally projecting flanges extending outwardly from the upper edges of its side walls, said flanges having openings therethrough, a series of twyer blocks arranged end to end along said flanges, each of said twyer blocks consisting of an elongated hollow member open only on the side overlying the adjacent flange, there being slots in the side of each of the twyer blocks facing inwardly with respect to the retort, and a dividing wall extending transversely 60 across the interior of each of said twyer blocks so as to form separate chambers each 65 having independent outlets into the retort.

In witness whereof, I hereunto subscribe my name this 23rd day of December, A. D. 70 1907.

WILLIAM J. KENNEY.
